UNITED STATES PATENT OFFICE.

FREDERICK S. TYSON, OF LOCK HAVEN, PENNSYLVANIA.

CHOCK.

1,248,955.

Specification of Letters Patent.

Patented Dec. 4, 1917.

Application filed May 7, 1917. Serial No. 166,811.

To all whom it may concern:

Be it known that I, FREDERICK S. TYSON, a citizen of the United States, residing at Lock Haven, in the county of Clinton and State of Pennsylvania, have invented certain new and useful Improvements in Chocks, of which the following is a specification.

My invention consists of an improved chock. One object of my invention is to provide a chock which will be particularly adapted for the transportation of automobiles and other vehicles in railroad cars, boats, etc.

Another object is to so construct my invention that the weight of the vehicle resting thereon will serve to increase the frictional engagement of the chock with the floor upon which it rests.

A further object is to so make my invention that it will be durable and of simple construction.

These objects, and other advantageous ends which will be described hereinafter, I attain in the following manner, reference being had to the accompanying drawings in which

Figure 1 is a side view of my invention showing a vehicle wheel resting thereon.

Fig. 2 is an enlarged section on the line 2-2 of Fig. 1.

Fig. 3 is an enlarged section on the line 3-3 of Fig. 1.

Fig. 4 is an enlarged section on the line 35 4-4 of Fig. 1.

Fig. 5 is a perspective view of my invention.

Referring to the drawings, 1 represents my improved chock which includes a base plate 2, preferably of strap sheet metal which is bent longitudinally in the arc of a circle so as to conform to the curvature of a vehicle wheel such as shown at 3 in Fig. 1.

One end of the base plate 2 is turned to provide an eye 4 through which extends the cylindrical transverse portion 5 of a substantially U-shaped standard 6. The lower ends 7 of the legs 8 and 9 of said standard are pointed so as to pierce or indent the floor 50 upon which it rests.

The opposite end 10 of the base plate 2 is formed by bending the metal of the base plate downwardly at an angle and I preferably crease and bend the lower end 11 to 55 provide a second standard in which the cor-

ners 12 and 13 will indent the floor as clearly shown in Fig. 3, it being noted that by creasing the standard 11 as indicated at 14, the creased portion will extend to a higher level than the corners 12 and 13, so that only the 60 corners 12 and 13 of the standard 11 will engage the floor.

I secure a clip 15 to the base plate 2 by means of two rivets 16 which have pointed heads 17 also designed to pierce the floor. 65 The clip 15 includes a transversely extending portion 18 and two legs 19 which are formed by bending the material of the clip upwardly above the upper surface of the plate 2 as shown at 20, and then downwardly as shown at 21, so that the free ends 22 of said legs are below the lower surface of the transversely extending portion 18 and will engage the floor.

The portions 21 of the legs 19 extend at an angle to the portions 20 and are spaced therefrom as shown at 23. This construction provides a resilient support so that the weight of the vehicle wheel tends both to force the free ends 22 of the legs 19 into the 70 floor and to slightly spread the legs. Furthermore, the portions of the legs 19 which extend above the upper surface of the plate 2, serve as retainers for the tire of the vehicle wheel to prevent lateral movement of 75 the latter relatively to the base plate.

To further guard against lateral movement and also to prevent a relative rotary movement between the bearing portion of the vehicle wheel and the base plate, I provide two clips 24 and 25. These two latter mentioned clips are similarly constructed and each includes a transversely extending portion 26 and two angular end portions 27.

Furthermore, these clips are preferably 80 secured by rivets and against the under surface of the base plate 2.

By providing a chock constructed in the manner above described, the standard 6 can be moved into various pivotal positions and the base plate 2 will accommodate itself to wheels of various diameters. Furthermore, the standards 6 and 11, clip 15, and rivets 17, all serve to frictionally engage the floor in such manner that the weight of the vehicle 100 serves to force said members into the floor and as above noted the arrangement of the legs 19 of the clip 15 will slightly spread or bow and thereby assist in preventing the slipping of the chock on the floor. 105

My invention is of comparatively simple construction, is durable, and efficiently performs its work.

While I have described my invention as taking a particular form, it will be understood that the various parts of my invention may be changed without departing from the spirit thereof, and hence I do not limit myself to the precise construction set forth, but consider that I am at liberty to make such changes and alterations as fairly come within the scope of the appended claims.

Having thus described my invention, what I claim as new and desire to secure by Letters Patent is:

1. A chock for vehicle wheels including an arcuate base plate made of sheet material and having an eye formed at one end, and a standard having a portion rotatably mounted in said eye, said standard also having a free end portion adapted to engage the floor, substantially as described.

2. A chock for vehicle wheels including an arcuate base plate and legs secured to said plate, said legs having portions extending above and below the plate, said upwardly extending portions providing clips to prevent lateral movement of a wheel on the plate, said downwardly extending portions being adapted to pierce the floor and

prevent lateral displacement of the plate, substantially as described.

3. A chock for vehicle wheels including a base plate, a clip, legs on said clip extending above and below said plate, and a pointed member on said base plate between said legs and designed to engage the floor upon which the chock rests, substantially as described. 35

4. A chock for vehicle wheels including a base plate, a standard extending downwardly from said base plate and being creased to provide sharp corner portions for engagement with the floor, substantially as described. 40

5. A chock for vehicle wheels including a base plate, a clip, legs on said clip extending above and below said plate, rivets securing the clip to the base plate and having pointed heads designed to pierce the floor upon which the chock rests, substantially as described. 45 50

In testimony whereof I have signed my name to this specification in the presence of two subscribing witnesses.

FREDERICK S. TYSON.
